UNITED STATES PATENT OFFICE.

KENNETH McLEOD, OF BROOKVILLE, PENNSYLVANIA.

TILE.

No. 895,884.

Specification of Letters Patent.

Patented Aug. 11, 1908.

Application filed August 29, 1906. Serial No. 332,510.

To all whom it may concern:

Be it known that I, KENNETH McLEOD, a citizen of the United States of America, residing at Brookville, in the county of Jefferson and State of Pennsylvania, have invented new and useful Improvements in Tiles, of which the following is a specification.

This invention relates to tiles, being especially directed to an anchoring member 10 or attachment designed for use in connection with the tile, and has for its objects to provide a simple, inexpensive device of this character which may be readily applied for use, one whereby the tile will be firmly and 15 securely locked or anchored in place, and one which will effectually hold the tile in place and prevent its falling in the event of the cement or like binding material failing to properly adhere to the back of the tile.

With these and other objects in view, the invention comprises the novel features of construction and combination of parts 20 more fully hereinafter described.

In the accompanying drawings: Figure 1 25 is a perspective view of a tile equipped with an anchoring member and showing one form of embodiment of the invention. Fig. 2 is a central, longitudinal section taken on the line 3—3 of Fig. 1. Fig. 3 is a perspective 30 view of the anchoring member.

Referring to the drawings, 1 designates a tile of usual form and material having formed in its reverse face or back and in appropriately spaced relation a plurality of 35 sockets or seats 2 shown as being of circular form and having undercut or dove-tailed marginal walls 3 adapted for engagement with the base portion 4 of a locking or anchoring member 5 which is formed from a 40 single piece or length of metal and in addition to the base portion embodies a diagonally inclined outwardly projecting portion or arm 6 terminating at its outer end in an engaging portion or finger 7 disposed in a 45 plane parallel with the adjacent face of the tile, it being understood in this connection that the base portion 4, which is of spring metal, is adapted for compression to be introduced into the seat 2 and when properly 50 seated expands for secure interlocking engagement with the undercut walls of the seat.

In practice, the tiles are laid in the usual manner by coating the reverse face or back 55 with plaster of paris or other cement and while the cement is in a plastic condition

pressing the tiles against the surface on which they are to be laid, it being evident that after the cement has set or hardened the anchoring members will be firmly and securely 60 embedded therein, thus to anchor the tiles in place, and furthermore, that in the event of the cement shrinking away from or otherwise failing to adhere properly to the face of the tile, the latter will be retained in place and 65 prevented from falling through the medium of the anchoring member or members. Furthermore, it is apparent that during the operation of coating the face of the tile with the cement the sockets or seats may be filled with 70 the latter, thus to securely fix the anchoring members to the tile.

In conclusion, it may be mentioned that heretofore it has been the practice to form tiles with a plurality of sockets or recesses 2 75 similar to those shown herein, these sockets being intended to become filled with the plastic cement in the operation of laying the tiles for the purpose of fixedly securing the latter in place. It has been found, however, 80 in practice that atmospheric pressure within the sockets prevents the cement from entering thereinto and that consequently the purpose for which the sockets are provided is wholly defeated and that the tiles consequently 85 fall in the event of the cement shrinking away from or failing to adhere to the rear face of the tile. Through my improved device these objections and difficulties are wholly overcome and provision is made for 90 properly and securely anchoring the tiles on the surface to which they are applied.

Having thus described my invention, what I claim is:

1. In combination with a tile having a 95 socket in its reverse face surrounded by an undercut wall, an anchoring device having a laterally expandable spring base sprung into said socket and engaging said undercut wall, and a portion projecting from said base and 100 the reverse face of the tile to be embedded in the mortar in which the tile is laid.

2. In combination with a tile having a socket in its reverse face surrounded by an undercut wall, an anchoring device having a 105 laterally expandable spring base sprung into said socket and engaging said wall, and a key portion projecting from said base and the reverse face of the tile and terminating in an arm parallel with such face of the tile to be 110 embedded in the mortar in which the tile is laid.

3. In combination with a tile having a socket in its reverse face surrounded by an undercut wall, an anchoring device made of a single piece of spring wire and comprising a substantially circular base open at one side for free lateral expansion and contraction and sprung into said socket and engaging said wall, a key portion projecting from one side of such base through the mouth of the socket and at an oblique angle beyond the

reverse face of the tile, and an arm at the outer end of said key portion extending substantially parallel with the reverse face of the tile.

In testimony whereof, I affix my signature 15
in presence of two witnesses.

KENNETH McLEOD.
